FIRING MECHANISM

Warren L. Nahm, Oakland, and George W. Brown, San Francisco, Calif., assignors to Bankers Protection Co., San Francisco, Calif., a corporation of Nevada

Application November 30, 1931
Serial No. 577,994

15 Claims. (Cl. 42—69)

This invention relates to a firing mechanism, such as used for firing percussion caps and the like, and particularly to a trigger actuated firing mechanism which is silent in operation.

5 In the operation of certain types of signalling devices, alarm devices, and the like, which are set off and ignited by means of a percussion cap or other ignition means, see for instance the alarm device disclosed in a co-pending application entitled "Security bag", Serial Number 561,980, filed September 9, 1931, it is desirable to provide a trigger actuated firing mechanism which is silent in operation as a delayed period is usually desirable before the signal or alarm 10 is given, that is, the firing of the percussion cap ignites a timing or delay action fuse and this, in turn, ignites an explosive charge which produces a visible smoke signal, and an audible alarm in the form of a shot or the like. Hence, as the signal or alarm is given a predetermined time 15 period after the firing of the percussion cap, silent operation of the firing mechanism is desirable to eliminate any suspicion or forewarning of the coming signal or alarm.

20 The object of the present invention is to generally improve and simplify the construction and operation of trigger actuated firing mechanisms of the character described; to provide a trigger actuated firing mechanism which is silent in operation; to provide a combination cocking and safety device whereby the trigger may be quickly and readily cocked and whereby the trigger may be locked against operation; to provide a firing mechanism in which the combination trigger 25 cocking and safety device is key actuated so that the key may be removed when the cocking device is turned to locked or safety position and thereby prevent tampering with or release of the trigger by unauthorized persons; and further, to provide a trigger actuated firing mechanism in which the firing pin is actuated so as to apply pressure to fire the percussion cap or other ignition means rather than a blow.

The firing mechanism is shown by way of illustration in the accompanying drawings in which—

Fig. 1 is a side elevation in section of the security bag showing the application of the firing mechanism.

Fig. 2 is a perspective view of the trigger.

50 Fig. 3 is a perspective view of the combination cocking and safety pin.

Fig. 4 is a perspective view of the key whereby the cocking and safety pin is actuated.

Fig. 5 is a vertical cross section taken on line 55 V—V of Fig. 7.

Fig. 6 is a vertical cross section taken on line VI—VI of Fig. 7.

Fig. 7 is an enlarged longitudinal vertical sectional view of the firing head and a portion of a cartridge case attached thereto, said view also 60 showing the trigger actuating mechanism whereby the firing head is actuated; this figure also shows the firing mechanism in cocked position and ready for firing.

Fig. 8 is a view similar to Fig. 7 but differing 65 therefrom in showing the firing mechanism tripped and the percussion caps fired.

Referring to the drawings in detail and particularly Fig. 1, A indicates a handbag having a bottom portion 2, and end portions 3 and 4. The 70 upper portion of the bag is provided with a pair of frames 5 which are pivotally connected at opposite ends as indicated at 6 to permit the bag to be opened and closed, the bag being further provided with handles such as indicated at 7 to 75 permit it to be readily carried. Formed interiorly of the bag and in one side thereof is a pocket generally indicated at B. This pocket forms a receptacle for a firing head C and a cartridge case D. The lower end of the pocket is open and so 80 is the registering portion of the bottom 2 of the bag so as to permit the cartridge case to be inserted or removed and also to permit shots and smoke to be discharged through the bottom of the bag as will hereinafter be described.

85 The firing head C contains a trigger 9, firing pins formed on the lever 10 which is pivotally mounted in the head as indicated at 11, and it further contains an actuating spring 12 and a series of links E which are tripped by the trigger 90 9. The trigger is, in this instance, operated through means of a trigger actuating mechanism generally indicated at F, this mechanism consisting of a pull wire 14a having a loop 14 formed at one end. The pull wire is attached to a 95 pivoted arm 15 and this is connected with the trigger 9 through means of a wire 16.

The bag illustrated in Fig. 1 is known as a security bag and it is particularly intended for the transfer of money and other valuables from 100 one bank or place of business to another. Messengers carrying valuables are from time to time stopped or interfered with by holdup men and the like and the purpose of the invention is that

of protecting the messenger, and secondly, that 105 of providing means for detecting or tracing the whereabouts of the holdup men after the bag has been taken from or surrendered by the messenger.

The messenger equipped with a bag of this 110

character carries the bag by means of the handles 7 and one finger is inserted through the loop 14 of the pull wire which actuates the trigger actuating mechanism generally indicated at F. 5 If the messenger is held up his instructions from his employers require him to freely hand the bag to the holdup man but, in so doing, he retains the loop 14 of the pull wire about his finger, thus in handing the bag to the holdup man he activates the trigger actuating mechanism and this, in turn, exerts a pull on the trigger 9. When this is pulled the trigger trips the firing mechanism in the firing head causing firing of the percussion caps indicated at 17. These ignite a quick 10 burning fuse indicated at 18 and this, in turn, ignites time or delay fuses, such as shown at 19 and 20; the fuses 19 igniting charges of explosive which fires a succession of shots and the fuses 20 igniting smoke ejecting charges. Hence, 15 if the bag is handed over to a holdup man, the trigger is released during the transfer of the bag without the holdup man being aware of the fact. The quick burning fuse is ignited and this ignites the delay action fuses 19 and 20, hence the holdup man will have an opportunity to get away with 20 or, at least, think that he is getting away with the bag before he is alarmed by the firing of the shots and the discharge of dense volumes of smoke from the bottom of the bag. In most instances it is very likely that the holdup man will 25 drop the bag and attempt to escape, but if he does not do so, his whereabouts can easily be traced due to the dense volumes of smoke discharging.

30 35 Due to the fact that the signal or alarm in the form of shots and smoke is given a predetermined time period after the firing of the percussion cap, silent operation of the trigger actuating mechanism and the firing mechanism is desirable to eliminate any suspicion or forewarning of the coming signal or alarm as protection to the messenger.

The firing mechanism enclosed within the head C is designed with this object in view. The 40 mechanism consists of a lever 10 pivotally mounted in the head C at the point indicated at 11. A pair of firing pins 10a are formed on the lever and these align with the percussion caps 17 so as to be forced into the heads of the caps when they are to be fired. The free end of the lever 10 upon which the firing pins are 45 mounted is connected through means of a link 25 with a triangular shaped plate 26 pivotally mounted in the head C as at 27; the link 25 being pivoted at its lower end to the lever 10 and at its upper end to the plate 26. This link functions in a manner similar to a toggle link as will 50 hereinafter be described. The triangular shaped plate 26 is in reality nothing more or less than a bell crank. It is swung about its pivot 27 in one direction by means of the spring 12 when the percussion caps are to be fired and it is swung in the opposite direction about the pivot 27 by means of a cocking mechanism hereinafter to be described. The spring 12 is mounted 55 within the barrel 28, one end of the barrel is pivotally attached to the plate or bell crank 26 at the point indicated at 29, the other end of the barrel is closed as shown and a rod 30 extends through the closed end. One end of the rod is secured by means of a head member 31 in the firing head. The opposite end of the rod is provided with a nut or head member 32 and the spring 12 is interposed between this head and the outer closed end of the barrel. Hence, the 60

action of the spring is that of imparting movement to the barrel in the direction of arrow a and as the barrel is pivotally connected to the bell crank 26, this will tend to swing about the pivot 27 in the direction of arrow b.

The position assumed by the firing mechanism prior to the firing of the percussion cap 17 is shown in Fig. 7. In this position link 25 assumes a slightly angular position but when the firing mechanism is tripped by the trigger 9 the bell crank 26 is swung in the direction of arrow b through means of the spring 12. When the bell crank assumes the position shown in Fig. 8, the link 25 will assume a substantially vertical position and movement is thus transmitted to the free end of the lever 10 causing this to swing about the pivot 11 in a downward direction thereby forcing the firing pins 10a into the head ends of the percussion caps 17 and firing the 95 same.

It was previously stated that the link 25 functioned as a toggle link. This is due to the fact that in conjunction with the bell crank 26 it has a motion similar to a toggle link and, further, because its movement is very slight and the pressure exerted gradually increases in an end-wise or downward direction. Such a movement is exceedingly desirable in a structure of this character where silent operation is required as it exerts a quick downward pressure on the lever 10 which forces the firing pins into the percussion caps, this movement being by far the more desirable when comparison is made with a hammer or the like, which produces a striking blow rather than pressure action such as here illustrated. The striking hammer is bound to make a clicking noise which can be heard while the quick downward pressure exerted in this instance is noiseless. The action of the spring 12 is also noiseless as it is completely enclosed within the barrel.

The cocking and tripping mechanism embodies the trigger 9, a link 35, and a second triangular shaped plate 36. The link 35 is pivotally attached at its lower end to a pin extending 120 through the firing head C. The upper end of the link is pivotally attached to the triangular plate 36 as indicated at 37 and the plate 37 is in turn pivotally attached as at 38 to the triangle shaped plate or bell crank 26.

The trigger 9 is best illustrated in Figs. 2, 7 and 8. It is secured on a shaft or pin 40 which is pivotally mounted in the head member C. One face of the pin is cut away, as indicated at 41, to form a cam surface and this surface is adapted to engage a projection or finger 42 formed on the triangular plate 36.

When the firing mechanism assumes the cocked position shown in Fig. 7, it should be noted that the pivotal connection 37 between the link 35 and the triangular plate 36 assumes a position slightly to one side of a center line drawn through the pivots 38 and 35a. In this position finger 42 engages the cam face 41 of the trigger pin but if the trigger is swung in the direction of arrow c by means of the pull wire 16 the cam 41 will engage the finger and impart a rocking movement to the triangular plate in the direction of arrow d. In so doing, the pivotal connection 37 swings to the other side of the center line and the mechanism is then tripped as the pull of the spring 12 will swing the bell crank 26 in the direction of arrow b and consequently swing the link 35 and triangular plate 36 in the direction of arrow d, thus caus-

ing them to assume the position shown in Fig. 8. In this position the firing mechanism is completely tripped and the percussion caps will have been fired, as the firing pins 10a are forced or driven into the ends of the caps.

In order that the firing mechanism may be quickly and readily cocked or reset after firing, a pin 50 is employed. This pin is best shown in Figs. 3, 7 and 8. The pin is journaled in the head member C. A portion of it is cut away, as indicated at 51, to form a cam surface. One end of the pin is provided with a tongue 52 and this is adapted to be engaged by the slotted end 53 of a key member which consists of a pin 54 and head 55, see Figs. 4 and 5. The key is insertable through an opening formed in the side of the head member and when inserted the slotted end 53 engages the tongue 52 formed on the end of the pin 50. By turning the head 55 of the key, turning movement is transmitted to the pin 50, and if it assumes the position shown in Fig. 8, the cam surface 51 will engage the link 35 and swing it from the position shown in Fig. 8 to the position shown in Fig. 7. During this movement the firing mechanism is reset or cocked.

The pin 50 forms two main functions, first, that of a cocking member to reset the firing mechanism, and secondly, that of a lock or a safety member to prevent tripping of the firing mechanism when desired. If the pin 50, after rotation, is left so that the cam member 51 engages with the link 35, as shown by dotted lines at 51a, in Fig. 7, the link 35 will be locked or held against movement in the direction of arrow d, hence locking the trigger 9 and the link 35 against operation. On the other hand, if it is desired to place the firing mechanism in readiness to be fired, pin 50 is rotated a half revolution, so that the cam 51 will assume the position shown in full lines in Fig. 7. In this position the trigger is operable and the firing mechanism may accordingly be tripped whenever desired.

In order that the pin 50 shall be retained in either the locking or the released position, flat surfaces, such as shown at 56, are formed on opposite sides of the pin. These are engaged by the spring detent, as indicated at 57, and the pin 50 is thus retained against accidental rotation when either position is assumed. The key as shown in Fig. 4, is also retained in the firing head against accidental removal. This is accomplished by forming an annular groove 58 in the pin into which a pin 59 projects. A straight slot 60 communicates with the annular groove 58, and when this is turned into register with the pin 59 the key may be removed. The head of the key is provided with two flat surfaces; on one surface is printed the word "fire" and on the other surface is printed the word "safe". The straight slot 60 will only register with the pin 59 when the key is turned to "safe" position; hence it is only in this position that the key may be removed.

The cartridge containing the explosive and smoke producing charge, and the percussion caps 17, may be secured to the head member C in any suitable manner, for instance, by screws such as shown at 70 in Fig. 6. The head member C will, under ordinary conditions, be permanently secured in the security bag and the cartridge case may accordingly be released or secured with relation to the head as desired.

From the foregoing, it will be noted that a firing mechanism has been provided which is silent

in operation; firing mechanism has been provided which can be quickly cocked or reset when desired; a firing mechanism has been provided which may be locked against operation and key actuated means are employed for actuating the locking or safety mechanism, said key when removed preventing tampering or release of the trigger mechanism by unauthorized individuals.

While certain features of the present invention are more or less specifically described, we wish it understood that various changes may be resorted to within the scope of the appended claims. Similarly, that the materials and finish of the several parts employed may be such as the manufacturer may decide, or varying conditions or uses may demand.

Having thus described our invention, what we claim and desire to secure by Letters Patent is—

1. A firing mechanism comprising a housing, a firing pin mounted in the housing, spring means and links connecting said spring means and firing pin whereby a gradually increasing pressure is applied to the pin while imparting end- 100 wise movement thereto.

2. A firing mechanism comprising a housing, a firing pin mounted in the housing, a toggle link connected with the pin whereby movement is imparted thereto, spring actuated means whereby movement is imparted to the toggle link in one direction, manually actuated means whereby movement is imparted to the toggle link in the opposite direction, trigger actuated means for releasing the toggle link to permit it to be actuated by the spring, and key actuated means for locking the trigger and toggle against movement. 110

3. A firing mechanism comprising a housing, a firing pin mounted in the housing, a toggle link 115 connected with the pin whereby movement is imparted thereto, spring actuated means whereby movement is imparted to the toggle link in one direction, manually actuated means whereby movement is imparted to the toggle link in the 120 opposite direction, trigger actuated means for releasing the toggle link to permit it to be actuated by the spring, and key actuated means for locking the toggle link against movement.

4. A firing mechanism comprising a housing, a 125 firing pin mounted in the housing, a toggle link connected with the pin whereby movement is imparted thereto, spring actuated means whereby movement is imparted to the toggle link in one direction, manually actuated means whereby 130 movement is imparted to the toggle link in the opposite direction, trigger actuated means for releasing the toggle link to permit it to be actuated by the spring, and key actuated means for locking the trigger against movement. 135

5. A firing mechanism comprising a housing, a firing pin mounted in the housing, a toggle link pivotally connected with the pin, a spring connected with the toggle link and exerting a pull to swing the toggle link in a direction which will 140 move the firing pin to firing position, manually actuated means whereby reverse movement is transmitted to the toggle link to reset the firing pin, said means also adapted to lock the toggle link and firing pin against movement, and means 145 for releasing the toggle link to permit the spring to actuate the same.

6. A firing mechanism comprising a housing, a firing pin mounted in the housing, a toggle link pivotally connected with the pin, a spring con- 150

nected with the toggle link and exerting a pull to swing the toggle link in a direction which will move the firing pin to firing position, manually actuated means whereby reverse movement is transmitted to the toggle link to reset the firing pin, said means also adapted to lock the toggle link and firing pin against movement, and trigger actuated means for releasing the toggle link to permit the spring to actuate the same when the manual means has been actuated to release the toggle link.

7. A firing mechanism comprising a housing, a lever pivotally mounted at one end in the housing, a firing pin on the free end of the lever, a bell crank pivotally mounted in the housing adjacent the free end of the lever, a spring connected with one arm of the bell crank, a link forming a pivotal connection between the arm of the bell crank and the free end of the lever, said link together with the bell crank arm forming a toggle link, a pair of pivotally connected links, one of said links being pivotally connected to the other arm of the bell crank, said link having a finger projection formed thereon, a pivoted connection between the other link and the housing, and a trigger engageable with the finger projection.

8. A firing mechanism comprising a housing, a lever pivotally mounted at one end in the housing, a firing pin on the free end of the lever, a bell crank pivotally mounted in the housing adjacent the free end of the lever, a spring connected with one arm of the bell crank, a link forming a pivotal connection between the arm of the bell crank and the free end of the lever, said link together with the bell crank arm forming a toggle link, a pair of pivotally connected links, one of said links being pivotally connected to the other arm of the bell crank, said link having a finger projection formed thereon, a pivoted connection between the other link and the housing, a trigger engageable with the finger projection, and a combination cocking and safety pin engageable with the last named pair of links.

9. A firing mechanism comprising a housing, a lever pivotally blunted at one end in the housing, a firing pin on the free end of the lever, a bell crank pivotally mounted in the housing adjacent the free end of the lever, a spring connected with one arm of the bell crank, a link forming a pivotal connection between the arm of the bell crank and the free end of the lever, said link together with the bell crank arm forming a toggle link, a pair of pivotally connected links,

one of said links being pivotally connected to the other arm of the bell crank, said link having a finger projection formed thereon, a pivoted connection between the other link and the housing, a trigger engageable with the finger projection, and a key whereby the combination cocking and safety pin is actuated. 80

10. In a device of the character described, a firing pin, a pair of pivoted links normally disposed at an angle to each other, one end of one 85 of said links engaging said firing pin, and means for urging said links toward a position of alignment to move the firing pin.

11. In a device of the character described, a housing, a firing pin in the housing, a normally 90 bent toggle joint connecting the housing and firing pin, and means for urging the toggle joint toward a straight position to move the firing pin relative to the housing and in a firing direction.

12. A device of the character described comprising a housing, a firing pin in the housing, a link pivoted to the housing, a link pivoted to the firing pin, a pivotal connection between said links, said three pivots normally being out of alignment, and means for urging said pivots toward a position 100 of alignment to move the firing pin.

13. A firing mechanism comprising a housing, a firing pin therein, a toggle link connected to the firing pin, a spring engaging the toggle link and normally urging it to impart firing movement 105 to said firing pin, means retaining the toggle link against movement by the spring, and trigger means for releasing said retaining means.

14. A firing mechanism comprising a housing, a firing pin therein, a toggle link connected to 110 the firing pin, a spring engaging the toggle link and normally urging it to impart firing movement to said firing pin, means retaining the toggle link against movement by the spring, trigger means for releasing said retaining means, and 115 means for locking said trigger means against releasing movement.

15. A firing mechanism comprising a housing, a firing pin therein, a toggle link connected to the firing pin, a spring engaging the toggle link 120 and normally urging it to impart firing movement to said firing pin, means retaining the toggle link against movement by the spring, trigger means for releasing said retaining means, and key actuated means for locking said trigger means 125 against releasing movement.
